Patented Feb. 16, 1971

219,941

CIGAR CUTTER

Gosta Swanson, Box 26, Hollis, N.H. 03049

Filed Feb. 19, 1970, Ser. No. 21,524

Term of patent 14 years

Int. Cl. D27—99

U.S. Cl. D85—7

Fig. 1.

Fig. 2.

Fig. 3.

Fig. 4.

Fig. 5.

Fig. 6.

FIG. 1 is a top perspective view of a cigar cutter embodying my new design;

FIG. 2 is a side elevational view, the opposite side being a mirror image of the side shown;

FIG. 3 is a front elevational view;

FIG. 4 is a rear elevational view;

FIG. 5 is a top plan view; and

FIG. 6 is a bottom plan view thereof.

I claim:

The ornamental design for a cigar cutter, substantially as shown and described.
